(57) **CLAIM**

The ornamental design for an ultrasonic cutter head, as shown and described.

DESCRIPTION

FIG. 1 is a top, front, and left side perspective view of an ultrasonic cutter head, showing our new design;

FIG. 2 is a top plan view thereof;

FIG. 3 is a left side view thereof;

FIG. 4 is a right side view thereof;

FIG. 5 is a bottom plan view thereof;

FIG. 6 is a front elevational view thereof;

FIG. 7 is a rear elevational view thereof; and,

FIG. 8 is a full view thereof.

The broken lines shown in FIGS. 1-5 and FIGS. 7-8 atop the cylinder illustrate boundaries of the ultrasonic cutter head. The additional broken lines shown in FIG. 8 illustrate environment and form no part of the claimed design.
